UNITED STATES PATENT OFFICE.

HERBERT R. PALMER, OF CLEVELAND, OHIO.

LAMP.

1,269,549.

Specification of Letters Patent. Patented June 11, 1918.

Application filed June 11, 1917. Serial No. 174,057.

To all whom it may concern:

Be it known that I, HERBERT R. PALMER, a citizen of the United States, residing at Cleveland, in the county of Cuyahoga and State of Ohio, have invented certain new and useful Improvements in Lamps, of which the following is a specification.

This invention relates to improvements in lamps of the character commonly known as head-lights that are used on motor-cycles, automobiles, motor-boats and other vehicles, and wherein electricity is employed as the medium for lighting the way in advance of the vehicle. While the lights of this character are adopted, more or less for the convenience of the occupants and drivers of the vehicles, there are numerous regulations or ordinances that must be complied with. These ordinances have particular reference to the lights used on automobiles and motor-cycles that are operated on streets or public high-ways, and the principal object of the present invention is to provide a lamp for this purpose that will meet all the requirements. A further object is the provision of an economical construction embodying means for meeting said requirements and enhancing the efficiency of the lamp.

My improvement provides for the obviating of the dazzling brightness or glare without diminishing the illuminating power of the lamp. It further provides simple and convenient means for focusing or adjusting the light member relative to other co-acting elements of the lamp. It also provides for universal adjustment of the lamp as a whole relative to its support and to the high-way. The improvement still further provides a secondary light member of comparative small dimensions and correspondingly low lighting capacity, which is operated independently of the main illuminating member for use when the vehicle is at rest for the purpose of identification or to denote the location of the vehicle when the main lights are extinguished. I am aware that small secondary light members have been used in connection with lamps for this purpose, but as heretofore constructed and arranged the secondary light member has been so located as to obstruct the rays and greatly diminish the illuminating efficiency of the main light member when said member was active, while my improved construction provides for a secondary light that does not interfere with the illuminating power of the lamp.

With the above and other apparent objects in view the invention consists in the general construction, arrangement and combination of the parts as hereinafter described and pointed out definitely in the claims, reference being had to the accompanying drawings in which similar characters of reference designate similar parts.

In the drawings Figure 1 is a front view of the improved lamp with a portion of the rim broken and the mounting trunnions not shown.

Fig. 2 is a central vertical section on line 1—1, Fig. 1.

Fig. 3 is a plan view of the improved lamp.

Fig. 4 is a section on line 4—4, Fig. 3.

Fig. 5 is a horizontal central section of the anti-glare elements assembled and detached from the lamp casing, and Fig. 6 is a perspective view of one of the blades used in the construction as hereinafter described.

In order to obtain the best results or the greatest efficiency through the co-acting of the different elements that enter into the general construction of the improved lamp, an adjustable mounting means is provided; to this end trunnions 1 are riveted, brazed, or welded to the lamp casing 2 on the same horizontal axis. These trunnions penetrate mounting blocks 3, being adjustable therein and when adjusted as desired they are made fast by set screws 4. The blocks 3 are provided with vertical openings adapted to accommodate the stems 5^a of the stationary fork 5 being vertically adjustable therein and made fast by set screws 6. By this arrangement the lamp casing is made applicable to forks varying in the dimensions between stems 5^a, and is also vertically, horizontally and angularly adjustable relative to its stationary support. This universal adjustability of the casing in combination with other features is a prominent factor of efficiency.

The illuminating member 7 is mounted in a suitable socket 8 that has a sliding bearing in the reflector member 9, as shown at 9^a. Fig. 2, and longitudinal adjustment of said socket and illuminating member is provided for by the screw 10 swiveled in the socket 8 and threaded in plate 11, which plate is adjustably attached to the casing 2.

The reflector member for projecting the light rays is made in a series of connected annular parts of different characteristics as

follows:—The portion .9 is parabolic, the portion 9^b is also parabolic, while the interposed part 9^c is circular. The functions of this composite reflector will presently be explained.

Attached to the front of the casing 2 is an extension barrel member 12; said member 12 provides retaining means for the transparent face 13 and also has confined 10 therein a grille member which is constructed as follows:—An annular shell 14 provided with a flange 14^a has segmental longitudinally extending partitions 15 and 16 arranged therein substantially as shown in 15 Fig. 1. These partitions are formed in segments having the same radial dimension as the annular shell 14, they are provided with flanges 15^a and 16^a and form a central opening adapted to accommodate or form a 20 frame for a prismatic glass member 17 of elliptical or cat's-eye shape as shown. The compartments 18 and 19 which surround the elliptical frame member are provided with longitudinal partitions or blades 20 arranged 25 parallel in horizontal planes, spaced apart and supported on each other by the members 20^a which are preferably integral with the blades 20 being cut and turned downward from the body of the blade, as best shown in Fig. 6. The blades 20 bear 30 on the flanges 14^a, 15^a and 16^a and being supported on each other form a durable and easily assembled structure which is held in the barrel member 12 by suitable means, as 35 for example binding spring devices 21. It will be noted that this novel construction provides for the members 20 being counterparts, that is, with the exception of a few that are located near the terminals of the 40 segments, they are all of the same dimension, they are therefore, with this exception, interchangeable, thus greatly facilitating the assembling of the device.

Centrally located in front of the illuminating member 7, and for convenience of assembling, attached to the members 15 and 16, is a shell 22; said shell is circular in cross-section and has a parabolic face 22^a. The shell 22 is so arranged that the outer periphery 22^b is in a longitudinal plane with the annular connection of the reflector members 9^b and 9^c, and the inner periphery 22^c is in the same plane as the connection of reflector members 9^c and 9.

It will be seen that light rays emanating 55 from the illuminating member 7 will be projected a longitudinal direction *a*, *a*, *a*, from the reflector 9^b. Rays will be projected in the direction *b*, *b* from reflector 9, and rays 60 from the parabolic member 22 will be projected as shown by *c*, *c*, while the reflector 9^c projects the rays diametrically through the illuminating member to the opposing parabolic portion 9^b; these rays then take 65 the direction *a*, *a*. This novel arrangement

of reflector members combined with the grille structure as above described provides a maximum of illuminating efficiency and obviates the glare by confining the direct or brilliant rays which produce the glare, to a 70 field of small vertical area and below the plane of vision. The light rays are projected on the high-way in advance of the lamp over an extended longitudinal field controlled by the vertical and angular adjustment of said lamp. The prismatic cat's-eye formation of the glass member 17 directs certain light rays to the high-way in close proximity to the front of the vehicle. 75

I am aware that the broad principle of applying a grille structure to the front of a head-light for the purpose of controlling the glare is not new in the art, but as far as I know the economical construction and arrangement of the elements that make up the 80 grille structure and the particular combination of said grille structure with the other lamp elements constructed and arranged as described is novel.

A secondary light member 23 of small 85 diameter, or substantially the same diameter as the socket 8 is located in front and in the longitudinal axial plane of the illuminating member 7 and the socket 8. A socket 24 is connected with the grille structure by 90 suitable means and is adapted to receive the stem of the light member 23 providing suitable electric connections therefor. The socket 8 is a one pole socket and is connected by the conductor 25 with a two pole socket 95 26 which is attached to the casing 2 and provides connecting means for the two pole plug 27. The socket 24 is also a one pole socket and is connected with the socket 26 by the conductor 28. Sockets 8 and 24 have ground 100 connection through the casing 2, and two conductors 25^a and 28^a connect the conductors 25 and 28 through the plug 27 with a suitable switch not shown.

It will be understood that there may be 110 modifications in the details of construction without affecting the co-operative arrangement of the several elements whereby the desired results are obtained, and while I have shown and described a lamp embodying a 115 construction that provides for the proper combination and arrangement, I am not confined to this specific construction only so far as limited by the scope of the claims.

What I claim and desire to secure by Letters Patent is:

1. In a lamp for the purpose set forth, the combination of an adjustable illuminating member; a composite reflector including a circular portion back of the illuminating member and a parabolic portion extending forward from the vertical plane of said member; a glare controlling member attached to the front of said reflector and comprising a supporting frame, a series of 120

- longitudinal partitions arranged in horizontal planes within and supported by said frame, and supported on each other by vertical members, said partitions surrounding an elliptical auxiliary frame which carries a prismatic glass member.
2. In a lamp for the purpose set forth, the combination of an adjustable illuminating member; a composite reflector including a circular portion back of the illuminating member and a parabolic portion extending forward from the vertical plane of said member; a glare controlling member attached to the front of said reflector and comprising a supporting frame, a series of longitudinal partitions arranged in horizontal planes within and supported by said frame, and supported on each other by vertical members, said partitions surrounding an elliptical auxiliary frame which carries a prismatic glass member; and a secondary light member back of the prismatic member in the longitudinal axial plane of the illuminating member.
3. In a lamp for the purpose set forth a glare controlling member attached to the front of the lamp and comprising a supporting frame, and a series of longitudinal partitions arranged in horizontal planes within and supported by said frame and supported

on each other by vertical members, said partitions surrounding an elliptical auxiliary frame which carries a prismatic glass member.

4. In a lamp for the purpose set forth a glare controlling member attached to the front of the lamp and comprising a supporting frame, and a series of longitudinal partitions arranged in horizontal planes within and supported by said frame and supported on each other by vertical members, said partitions surrounding an elliptical auxiliary frame comprising segments having the same radial dimension as the annular frame, said auxiliary frame carrying a prismatic glass member.

5. In a lamp for the purpose set forth a glare controlling member attached to the front of the lamp and comprising an annular supporting frame, and an elliptical auxiliary frame comprising segments having the same radial dimension as the annular frame, a series of longitudinal partitions arranged in horizontal planes within the annular frame surrounding the auxiliary frame and supported by said annular and auxiliary frames.

In testimony whereof I affix my signature.

HERBERT R. PALMER.
